CLAIM

The ornamental design for a wearable camera, as shown and described.

DESCRIPTION

FIG. 1 is a front, left, top perspective view of a wearable camera showing my new design;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof;
FIG. 8 is a front, right, top perspective view thereof;
FIG. 9 is a front, left, bottom perspective view thereof; and,
FIG. 10 is a front, right, bottom perspective view thereof.
The broken lines shown in the drawings depict portions of the wearable camera that form no part of the claimed design.
The broken away symbols in the drawings indicate that any portion of the article beyond what is shown forms no part of the claimed design.

1 Claim, 10 Drawing Sheets
